ALPHABET FOR SIGNS

Edward Brozen, New York, N. Y.

Application November 17, 1951, Serial No. 17,462

Term of patent 7 years

(Cl. D64—12)

To all whom it may concern:

Be it known that I, Edward Brozen, a citizen of the United States and a resident of the city, county, and State of New York, have invented a new, original, and ornamental Design for an Alphabet for Signs, of which the following is a specification, reference being had to the accompanying drawing, forming part thereof.

The drawing shows perspective views of an alphabet for signs, illustrating my new design.

The drawing is lined for the color red.

I claim:

The ornamental design for an alphabet for signs, substantially as shown and described.

EDWARD BROZEN.
